UNITED STATES PATENT OFFICE.

OSCAR LOEWENBACH, OF MILWAUKEE, WISCONSIN.

MANIFOLD SHEET AND BOOK.

1,162,376.

Specification of Letters Patent. Patented Nov. 30, 1915.

Application filed December 18, 1913. Serial No. 807,377.

To all whom it may concern:

Be it known that I, OSCAR LOEWENBACH, a citizen of the United States, and resident of Milwaukee, in the county of Milwaukee and State of Wisconsin, have invented certain new and useful Improvements in Manifold Sheets and Books; and I do hereby declare that the following is a full, clear, and exact description thereof.

10 My invention consists in what is herein particularly set forth with reference to the accompanying drawings and pointed out in the claim of this specification, its object being to meet a trade demand for economical 15 one piece manifold record sheets, (separate or bound) each having transparent and opaque record divisions, and it is preferable to perforate each sheet between the transparent and opaque divisions thereof to facilitate 20 separation of said divisions.

Figure 1 of the drawings represents a plan view of one of my improved manifold sheets for a record in triplicate; Fig. 2, a perspective view of an open book of similar 25 sheets folded and containing a sheet of carbon-paper in position between transparent and opaque divisions of the uppermost manifold sheet of which a portion of said transparent division thereof is partly broken 30 away, and Fig. 3, an edge view of one of the folded sheets having the carbon paper inserted between transparent and opaque divisions thereof.

Referring by numerals to the drawings 4 35 indicates a transparent record division, and 5 and 6 respectively indicate one of two opaque record divisions of a one piece three-division manifold sheet. It is preferable, as herein shown, to perforate the sheet cross- 40 wise of the same at 7 and 8 between divisions thereof to facilitate a separation of said divisions.

For binding, triplicate division manifold record sheets in accordance with my invention 45 may be severally folded, as herein shown, to provide each with a margin 9 for stitching, stapling or otherwise connecting it with others of a group to a back or cover, a cover 10 being illustrated, or the margin 50 9 may be impaled on pins or posts of a temporary binder. The uppermost division of

each folded sheet in a book is free of the binding and it is preferable to fold said sheet so that a portion of its under division extends beyond the others thereof at an edge 55 of the book.

In practice a single sheet 11 of carbon-paper (carbonized on both sides or folded to expose over and under carbon surfaces) is placed between the underlying transparent 60 and opaque divisions 4 and 6 of a properly folded triplicate division manifold record sheet in accordance with my invention, and the writing is done upon the uppermost opaque division 5 of said sheet. As a result 65 of the writing, there are carbon facsimiles upon the upper side of the undermost opaque division of the sheet and upon the underside of the transparent division of said sheet through which it may be read, and 70 thereafter any one or more of said divisions may be separated from the remainder thereof. By having the underlying division of each of a group of folded and bound sheets extended, as aforesaid, the finding of the 75 place in which to insert the carbon-paper is facilitated.

From the foregoing it will be understood that at least two copies of the readily obtained once-written record are upon opaque 80 divisions of the same folded manifold sheet in accordance with my invention, and these divisions of said sheet are best adapted for general business purposes, especially when subjected to considerable handling, the writing being plainer and less fugitive thereon. 85 My invention also enables me to economically furnish manifold record sheets, and books of the same, in which the paper stock is generally heavier and of better quality 90 than is ordinarily the case.

I claim:

A manifold record sheet having longitudinally arranged divisions, the end divisions being opaque, and the intermediate 95 division being transparent, one end division being separated from the transparent division by a transversely arranged combined fold and separation line, a margin portion being interposed between the other opaque 100 division and the transparent division, the margin having a transversely arranged cen-

trally disposed fold line, and at the junction of said margin and the last mentioned opaque division, a transversely arranged combined fold and separation line being
5 provided.

In testimony that I claim the foregoing I have hereunto set my hand at Milwaukee in

the county of Milwaukee and State of Wisconsin in the presence of two witnesses.

OSCAR LOEWENBACH.

Witnesses:

N. E. OLIPHANT,
M. E. DOWNEY.
